UNITED STATES PATENT OFFICE.

JOHN F. LYONS, OF HYDE PARK, MASSACHUSETTS; ASSIGNEE TO B. F. STURTEVANT COMPANY, OF BOSTON, MASSACHUSETTS, A CORPORATION OF MASSACHUSETTS.

MACHINE FOR MILLING TURBINE-BUCKETS.

1,081,242.

Specification of Letters Patent.

Patented Dec. 9, 1913.

Application filed January 25, 1912. Serial No. 673,366.

To all whom it may concern:

Be it known that I, JOHN F. LYONS, a citizen of the United States, residing at Hyde Park, in the county of Norfolk and State of Massachusetts, have invented certain new and useful Improvements in Machines for Milling Turbine-Buckets; and I do hereby declare the following to be a full, clear, and exact description of the invention, such as will enable others skilled in the art to which it appertains to make and use the same.

The present invention relates to machines for milling turbine buckets, and more particularly to machines for milling inclined buckets in the solid metal faces of the bucket-carrying parts of an elastic-fluid turbine, such as a steam turbine.

The buckets of the type which the machine of the present invention is arranged to mill are shown in Figures 4 and 5 of the patent to William E. Snow, 1,007,249, granted October 31, 1911, and in Figs. 4 and 5 of the patent to William E. Snow, 1,013,080, granted December 26, 1911. As particularly illustrated in the Snow patents, the lips which form the partition walls between the buckets have semi-circular notches cut in them. These notches are cut for the purpose of accommodating the supporting shaft or stud of the milling cutter which is used to mill the buckets. The milling cutter used in milling the buckets shown in the Snow patents consists of a circular cutter rigidly carried on the end of a supporting stud or shaft upon which cutting teeth are formed adjacent the cutter so that when the stud reaches the edge of the partition wall it mills the semi-circular notch in the edge of the partition wall so that the cutter can sink itself far enough into the metal to mill out a bucket having a semi-circular periphery or bottom to reverse the direction of flow of motive fluid. If the buckets can be milled so that no notch is cut in the edge of the partitions, the partitions will be stronger and will more effectually prevent the leakage of the motive fluid from one bucket to another.

With the object, therefore, of milling out semi-circular inclined turbine buckets in solid material having the edges of their partition walls continuous, the present invention consists in a milling machine having a milling cutter arranged to mill out a bucket

cavity having its bottom forming a substantially semi-cylindrical cavity with unbroken end walls.

Other features of the invention consist in certain devices, arrangements and combinations of parts hereinafter described, the advantages of which will be apparent to one skilled in the art from the following description:

Referring to the drawings, in which the preferred embodiment of the present invention is illustrated: Fig. 1 is a front elevation of the milling machine showing half of a twin machine; Fig. 2 is a side elevation looking from the right hand side of the machine; Fig. 3 is a plan view showing the work support and a turbine wheel mounted thereon, and also showing in section the milling cutter performing the first cutting operation in forming the buckets; Fig. 4 is a vertical section on the line 4—4 of Fig. 3; Fig. 5 is an enlarged sectional view showing the milling cutter performing the second cutting operation in forming the buckets; Fig. 6 is a detail view showing the gear connection for driving the milling cutter; Fig. 7 is a fragmentary view of the peripheral face of the turbine wheel after the buckets are milled; Fig. 8 is a section on the line 8—8 of Fig. 7; and Fig. 9 is a section on the line 9—9 of Fig. 8.

The buckets are cut by means of a circular milling cutter 1 having flat end faces 2 and 3 and teeth 4 formed on its periphery. The cutter has a counter sunk bearing in which is received a headed stud 6 which forms a supporting journal for the cutter and the flat head 8 of which is received in the countersink in the face 2 of the cutter. The stud 6 is held in a supporting sleeve 10 which is carried on the machine frame. The end face of the sleeve 10 next the cutter forms a semi-annular bearing surface 11 against one end face of the cutter so that the cutter is held from tilting but is free to rotate about the stud 6. The stud 6 is held in the sleeve 10 by means of the reduced screw-threaded end 12 projecting through the end of the sleeve 10 opposite the cutter and receiving a clamping nut 14. The stud 6 is positioned in the sleeve 10 by means of a slot cut in its side which receives the pin 16 driven through the side of the sleeve 10. The head 8 of the stud 6 is flush with the end face 2 of the cutter toward the work so that this face of the cutter

is entirely free of all projections. The stud 6 has its side next the work cut away (adjacent the other end face 3 of the cutter) to form a substantially V-shaped notch 18 which extends to the center of the stud. One wall 20 of the notch is flush with the end face 3 of the milling cutter so that this face of the milling cutter is free of projections for a complete semi-circular sector next the work. The other wall of the notch is cut at an angle so that it is substantially tangential to the work. The sleeve 10 has a notch 24 cut in it which coincides with the notch 18 so that the milling cutter 1, the stud 6 and sleeve 10 combined form a V-shaped notch adapted to receive the wedge-shaped portion of the work between the inclined bucket being milled and the surface of the work. The cutter 1 can, therefore, mill a bucket which 20 is inclined to the surface of the work and in which the cutter can sink up to the axis of the cutter on the face 3 of the cutter and beyond the axis of the cutter on the face 2 of the cutter. The teeth 4 of the milling cutter not only form cutting teeth, but also form the teeth of a worm gear wheel. The front edges 26 of the teeth 4 form the cutting edges of the milling cutter, while the backs 28 of the teeth 4 form contact surfaces 30 against which bears the thread of the worm 32 which drives the cutter. The worm 32 is formed on the lower end of a shaft 34 which is supported in bearing sleeves 36 and 38 and carries a spiral gear 40 on its upper end. 35 The gear 40 is driven from a spiral gear idler 41 which in turn meshes and is driven from a spiral gear 42 which is carried on the forward end of a shaft 43 which bears a cone pulley 44 belted to a cone pulley 46 on the main driving shaft 48 of the machine, which by means of a pulley 49 is belt driven from a suitable source of power. The bearing sleeves 36 and 38 are formed on a plate 50 which is pivoted about the axis of the spiral 45 gear wheel 41 and is arranged to be clamped in position by a clamping bolt 52 received through a curved slot. By means of the plate 50, the worm 32 can be moved relatively to the cutter 4 so that cutters of different diameters may be employed.

The turbine wheel 60 upon which the milling machine is illustrated as operating, is a single forging having a flanged rim 62 in the periphery of which the buckets are to be cut. The wheel 60 is supported and fed to the milling cutter by means of a work support indicated generally by reference character 64. The work support 64 comprises a turret 66, a slide 68 supporting the turret, a second slide 70 supporting the slide 68 and in turn supported upon the bench 72 formed on the machine frame. The wheel 60 is held on the turret 66 by means of a clamping bolt 74 which is received through the hub of the wheel 60 and by clamping bolts 76, the heads

of which are received in recesses 78 cut in the sides of two intersecting grooves 80 in the upper face of the turret and which bear on their upper ends nuts 82 which press the clips 84 against the upper edge of the rim 70. 62. The turret is rotatably mounted on the slide 68 by means of a downwardly projecting annular flange 86 which is received in an annular groove in the slide 68. Secured by means of screws 88 to the annular flange 75 86 is a ring 90 in the periphery of which are cut gear teeth which are arranged to mesh with a worm 92 by means of which the turret 66 is rotated. The worm 92 is carried on a horizontal shaft 94 which bears on its forward end a gear wheel 96. The gear wheel 96 is driven through an idler 98 from a gear wheel 100 which is provided with a handle 102. The handle 102 is provided with a spring pressed pin 104 which is arranged to engage in a recess 106 formed in a plate 108 on the machine frame. The idler 98 is mounted on a stud received in a curved slot 110 concentric with the gear 96 so that gears of different sizes may be used as the gear 90 wheel 100. A gear wheel 100 is selected of such a size that one or more complete revolutions of the handle 102 will turn the turret forward after each milling operation to present the turbine wheel in position for the 95 milling cutter to operate to cut the next bucket.

The slide 68 is mounted to reciprocate on the slide 70 in a direction at right angles to the feed of the work by means of a dovetail 120. The slide 68 is positioned laterally of the line of feed by means of the worm 122 which is arranged to be turned manually by the handle 124.

The slide 70 is mounted to reciprocate in the direction of feed of the work by means of a dove-tail 130. The slide 70 is reciprocated to feed the work to the milling cutter by means of a worm 132 held between two downwardly projecting lugs 134 on the slide 110 70 and meshing with a rack 136 on the machine frame. The worm 132 is turned to feed the work by means of a shaft 137 upon which it is loosely splined. The forward end of the shaft 137 carries an incased gear 115 wheel 138 which is driven from a worm 139 carried upon the shaft 140 which is journaled in lugs 142, 143 and 144 on the machine frame. The shaft 140 is arranged to be rotated either by power or by hand in 120 feeding the work. The shaft 140 is arranged to be power driven by means of a double crown wheel 146 which is loosely splined upon it and is arranged to engage two crown wheels 148 and 150 loosely journaled on the shaft 140 and arranged respectively to feed the work and to return the work after the feeding movement. The crown wheel 148 bears a gear 152 which meshes with a gear wheel 154 carried on a 130

shaft 155 which bears on its rear end the cone pulley 156. The pulley 156 is belt driven from a cone pulley 158 which is in turn belt driven from the pulley 44 at the top of the machine. The belts are so arranged that the gear 152 is slowly driven to feed the work slowly to the milling cutter. The crown wheel 150 bears a pulley face 170 which is arranged to be belted directly to a large pulley wheel 172 on the main driving shaft so that it is rapidly driven to quickly return the work after the milling operation.

The shaft 140 is arranged to be manually turned to feed the work by means of a crown wheel 180 loosely splined on the shaft and arranged to engage a second crown wheel 182 which fits over the end of the shaft 140 and is rotatably mounted in the lug 184 on the machine frame. The crown wheel 182 is arranged to be turned by means of the bevel gear wheel 186 meshing with a bevel gear 188 on the crown wheel, the shaft 190, the bevel gears 192 and the hand wheel 194, which is placed at the front of the machine. Mechanism is provided for engaging and disengaging the crown wheels 146, 148, 150, 180 and 182 so that the shaft 140 may be turned by hand or may be driven slowly by power to feed the work or may be rapidly driven by power for the return feed after the bucket is cut. This mechanism comprises two levers 200 and 202 which are pivoted to the machine frame at 204 and 206 respectively and which bear pins engaging peripheral slots in the crown wheels 146 and 180 respectively. A rod 208 connects the lower end of the lever 200 to a bell crank lever 210 on which is formed the handle 212. When the handle 212 is raised, the splined crown wheel 146 is thrown into mesh with the crown wheel 148 and the work is slowly fed forward by power. When the handle 212 is depressed, the crown wheel 148 is brought into mesh with the crown wheel 150 and the work is given a quick power driven return stroke from the feed. When the handle 212 is in intermediate position, as illustrated in Fig. 2, the crown wheel 146 is not meshed with either of the power driven crown wheels 148 or 150. A connection is provided between the rod 208 and the crown wheel 180 so that when the handle 212 is in intermediate position, the crown wheel 180 will mesh with the crown wheel 182, but when the handle 212 is thrown up or down the crown wheel 180 will not mesh with the crown wheel 182. This connection comprises a link 220 pivotally connected at 222 and 224 to the rod 208 and the lever 202 respectively. The link 220 has a projecting arm 226 which is arranged to contact with the rod 208 when the rod is moved to the right as viewed in Fig. 2, and a pin 228 which is arranged to

contact with the link 220 when the rod is moved to the left. When the rod 208 is moved to the left by the raising of the handle 212 the link 220 is brought against the pin 228 which acts as a pivot for the link 220 and through the lever 202 slides the splined crown wheel 180 out of engagement with the teeth of the crown wheel 182. When the rod 208 is moved to the right by the depression of the handle 212, the arm 226 is brought into contact with the rod 208 and serves to move the link 220 bodily to the right and through the lever 202 slides the crown wheel 180 out of engagement with the crown wheel 182. When the rod 208 is in intermediate position, as illustrated in Fig. 2, the arm 226 and pin 228 act to hold the link 220 in the position illustrated and so hold the crown wheel 180 in mesh with the crown wheel 182.

The operation of the machine is as follows: The turbine wheel 60 is clamped in place on the turret 66 and the handles 124 and 194 are turned to properly present the rim 62 of the wheel to the milling cutter. The handle 212 is then thrown up to feed the work to the milling cutter 1. After the first bucket is milled, the handle 102 is turned to position the work for the milling of the next bucket and so on until a series of buckets like those shown at 250 on Fig. 3 are cut out. Since the end faces 2 and 3 of the milling cutter are flat, the bucket as milled during the first operation has a semi-cylindrical bottom portion having its flat end walls parallel to each other so that the partitions 252 are thicker near their edges than at the bottom of the bucket. As clearly shown in Figs. 3 and 5, the cutter 1 mills a recess or bucket 250 which is inclined to the surface of the work and in which the face 3 of the cutter sinks up to the axis of the cutter and in which the face 2 of the cutter sinks beyond the axis of the cutter. The bucket 250 has a bottom portion 260 which is undercut beneath the partition 252 and a mouth portion 262 which lies to the left, as viewed in Fig. 5, of the edge of the overhanging partition 252. The bottom portion 260 is semi-cylindrical in shape. The curved side wall 264 of the bottom portion is a concave semi-cylindrical surface. The end wall 266 of the bucket which is next the end face 3 of the cutter is a complete semi-circular sector. The end wall 268 of the bucket which is next the end face 2 of the cutter may be considered as divided into two parts, namely, the part 270, which lies beneath the partition 252 and which is a complete semi-circular sector forming the end wall of the bottom portion 260, and the part 272 which lies, as viewed in Fig. 3, to the left of the edge of the partition 252 and which is rectangular in outline and forms the end wall of the mouth portion 262 of the

bucket. It is therefore evident that the wall 268 is rectangular at the mouth of the bucket and terminates in a semi-circular part at the bottom portion of the bucket. 5 The sides 274 of the mouth portion 262 are parallel and triangular in outline and form continuations of the curved side wall 264 of the bottom portion of the bucket. To mill the partitions 252 to a uniform thickness 10 the support is adjusted to present the periphery of the turbine wheel 60 at a slightly different angle to the milling cutter, as illustrated in Fig. 5. The cutter 1 then acts to mill off one side of the partitions 252 so that 15 they are of the same thickness near their edges as at the bottom of the buckets, as shown at the right hand side of the work illustrated in Fig. 5 and the flat end walls of the buckets are slightly divergent. Then 20 after the above described milling operations are completed, the edges of the lips 252 are filed down to a comparatively sharp edge and the buckets are carefully smoothed so that the buckets on the completed wheel 25 are like those shown in Fig. 8 of the drawings. As illustrated in Figs. 7, 8 and 9, the completed buckets 350 resemble the buckets 250 cut by the first milling operation except that their end walls 366 and 370 are slightly 30 divergent. The completed buckets have a mouth portion 362 bounded on either side by parallel triangular side walls 374 and having a rectangular end wall 372. Each bucket terminates in a bottom portion 360 35 which is undercut beneath the partition 252 and which constitutes an open-mouthed substantially semi-cylindrical cavity. Since the edge of the partition 252 is straight and unbroken, the two flat and slightly divergent end walls 366 and 370 of the bottom portion 360 form complete and unbroken semi-circular sectors. The side wall 364 of the bottom portion 360 is an unbroken concave semi-cylindrical surface which is continued beyond the edge of the partition 252 40 to form the triangular side walls 374 of the mouth portion of the bucket. The length of the bucket 250, or the space between the end walls 266 and 268 which the cutter can 45 occupy, is determined by the length of the cutter teeth 4 measured axially of the cutter. Therefore, in order that the cutter may sink into the work, as illustrated in Fig. 3, it is necessary that one end face of the cutter 50 must be free, for a complete semi-circular sector, of projections which would extend, either from the end face of the cutter itself, or from the wall 20 of the notch 18 in the stud 6, beyond a plane which is normal to 55 the axis of the cutter and which passes through the corners of the cutter teeth, and that the other end face of the cutter must be free, for more than a semi-circular sector, of projections which would extend, 60 either from the end face of the cutter itself 65

or from the head 8 of the stud 6, beyond a plane which, like the first plane, is normal to the axis of the cutter and which passes through the other corners of the cutter teeth. In the illustrated embodiment of the invention, 70 the two end faces 2 and 3 of the cutter are flat and the wall 20 of the notch 18 and the end of the stud head 8 are flat surfaces flush respectively with the faces 3 and 2 of the cutter. It is obvious, however, that it is 75 not necessary that the faces 2 and 3 of the cutter, or the wall 20 of the notch 18, or the end of the stud head 8 be flat surfaces so long as they are free of projections which would extend axially of the cutter beyond 80 the cutter teeth. Therefore, the expression "free of projections" as employed in the specification and claims with reference to the milling cutter is intended to define a construction in which there are no projections extending either from the cutter itself, 85 or from the journal upon which the cutter is mounted, axially of the cutter beyond the cutter teeth. In machining the wheel 60, either before or after the buckets are 90 formed, the middle of the periphery of the rim is turned down so that a slight projecting flange 280 is formed on either side of the line of buckets.

The present invention is not limited to the 95 details of construction of the preferred form of the invention above specifically illustrated and described, but may be otherwise embodied within the spirit of the invention as set forth in the following claims.

I claim—

1. A machine for milling turbine buckets, having, in combination, a circular milling center, a stud forming a supporting journal for the cutter and having its side next the work cut away adjacent the cutter to permit the cutter to mill a bucket having its bottom portion forming a substantially semi-cylindrical cavity with unbroken substantially semi-circular end walls, a work support, and means for causing a relative feeding movement between the work and the milling cutter, substantially as described.

2. A machine for milling turbine buckets, having, in combination, a circular milling cutter, a stud forming a supporting journal for the cutter and having its side next the work cut away adjacent the cutter to permit the cutter to mill a bucket having its bottom portion forming a substantially semi-cylindrical cavity with unbroken substantially semi-circular end walls, means engaging the cutter on the side opposite the work for driving the cutter, a work support, and means for causing a relative feeding movement between the work and the milling cutter, substantially as described.

3. A machine for milling turbine buckets, having, in combination, a circular toothed milling cutter, a stud forming a supporting

journal for the cutter and having its side next the work cut away adjacent the cutter to permit the cutter to mill a bucket having its bottom portion forming a substantially 5 semi-cylindrical cavity with unbroken substantially semi-circular end walls, a power driven rotary member meshing with the teeth of the cutter on the side opposite the work for driving the cutter, a work support, 10 and means for causing a relative feeding movement between the work and the milling cutter, substantially as described.

4. A machine for milling turbine buckets, having, in combination, a circular milling cutter having a countersunk bearing, a headed stud forming a supporting journal for the cutter, having its head received in the countersink to leave one face of the cutter entirely free of projections and having 15 its side next the work adjacent the other face of the cutter cut away to leave the second face of the cutter entirely free of projections for a complete semicircular sector next the work, means for driving the cutter, 20 a work support, and means for causing a relative feeding movement between the work and the milling cutter, substantially as described.

5. A machine for milling turbine buckets, having, in combination, a circular milling cutter having a countersunk bearing, a headed stud forming a supporting journal for the cutter, having its head received in the countersink flush with one face of the cutter 30 to leave said face entirely free of projections and having a notch cut in its side adjacent the other face of the cutter, one face of the notch being substantially flush with the side of the cutter to leave said face of the cutter 35 free of projections for a substantially complete semi-circular sector next the work, whereby the cutter is permitted to cut a bucket inclined to the surface of the work and having its bottom portion forming a 40 substantially semi-cylindrical cavity with unbroken substantially semi-circular end walls, means engaging the cutter on the side opposite the work for driving the cutter, a work support, and means for causing a relative 45 feeding movement between the work and the milling cutter, substantially as described.

6. A machine for milling turbine buckets, having, in combination, a circular milling cutter having its teeth forming gear teeth, a power driven member meshing with the cutter teeth for driving the cutter and a journal for the cutter projecting beyond one end face only of the cutter, substantially 50 as described.

7. A machine for milling turbine buckets, having, in combination, a circular milling cutter, and means for supporting and driving the cutter leaving one end face of the 55 cutter free of projections for a substantially

complete semi-circular sector next to the work and leaving the other end face of the cutter free from projections for more than a semi-circular sector next the work, substantially as described.

8. A machine for milling turbine buckets, having, in combination, a circular milling cutter having one side of its teeth shaped to form worm gear teeth and a worm meshing with the teeth of the milling cutter for driving the cutter, substantially as described.

9. A machine for milling turbine buckets, having, in combination, a circular milling cutter having its cutting teeth also forming the teeth of a gear, a stud forming a supporting journal for the cutter having its side next the work cut away adjacent the cutter to permit the cutter to mill a bucket having its bottom portion forming a substantially semi-cylindrical cavity with unbroken substantially semi-circular end walls, a power driven member engaging the teeth of the cutter on the side opposite the work for driving the cutter, a work support, and means for causing a relative feeding movement between the work and the milling cutter, substantially as described.

10. A machine for milling turbine buckets, having, in combination, a circular milling cutter also having its teeth forming the teeth of a worm gear, a stud forming a supporting journal for the cutter having its side next the work cut away adjacent the cutter to permit the cutter to mill a bucket having its bottom portion forming a substantially semi-cylindrical cavity with unbroken substantially semi-circular end walls, a worm engaging the teeth of the cutter on the side opposite the work for driving the cutter, a work support, and means for causing a relative feeding movement between the work and the milling cutter, substantially as described.

11. A machine for milling turbine buckets, having, in combination, a circular milling cutter, a headed stud forming a supporting journal for the cutter having its head received in the countersink to leave one face of the cutter entirely free of projections and having its side between its axis and the work cut away adjacent the other face of the cutter to leave the other face of the cutter entirely free of projections for a substantially complete semi-circular sector next the work, a supporting sleeve in which the stud is received having its end face next the cutter forming a bearing surface to coöperate with the stud head to hold the cutter and having its side next the work cut away to form a notch coincident with the cut-away portion of the stud, means engaging the cutter on the side opposite the work for driving the cutter, a work support, and means for causing a relative feeding move-

ment between the work and the milling cutter, substantially as described.

12. A machine for milling turbine buckets, having, in combination, a circular milling cutter, and means for supporting and driving the cutter including a journal upon which the cutter is mounted to rotate and which is so cut away next the work that one end face of the cutter is free of projections for a substantially complete semi-circular sector next the work and the other end face of the cutter is free from projections for more than a semi-circular sector next to the work, so that the cutter may mill an inclined bucket in the work into which the cutter may sink substantially to its axis

at one end of the cutter and beyond its axis at the other end of the cutter, substantially as described.

13. A machine for milling turbine buckets, having, in combination, a milling cutter, means for driving the cutter, and a support for presenting the cutter in position to mill an inclined bucket, said support having a notch for receiving the wedge-shaped portion of the work between the inclined bucket being milled and the surface of the work, substantially as described.

Correction in Letters Patent No. 1,081,242.

It is hereby certified that in Letters Patent No. 1,081,242, granted December 9, 1913, upon the application of John F. Lyons, of Hyde Park, Massachusetts, for an improvement in "Machines for Milling Turbine-Buckets," an error appears in the printed specification requiring correction as follows: Page 4, line 104, for the word "center" read *cutter*; and that the said Letters Patent should be read with this correction therein that the same may conform to the record of the case in the Patent Office.

Signed and sealed this 6th day of January, A. D., 1914.

[SEAL.]

J. T. NEWTON,
Acting Commissioner of Patents.
